ELECTRON DISCHARGE MODULATING
DEVICEDonald G. Haines, Owensboro, Ky., assignor to
Radio Corporation of America, a corporation of
DelawareApplication March 28, 1933, Serial No. 663,171
Renewed December 24, 1937

25 Claims. (Cl. 250—27.5)

This invention relates to electron discharge devices for superheterodyne reception and more particularly to a multi-electrode electron discharge tube in which local oscillations of a predetermined frequency and input oscillations of a different frequency, such as a radio signal, are mixed or combined directly in the tube without capacitive, inductive, or direct coupling of the oscillator and output circuits associated with the tube.

10 Usual methods of heterodyne reception use a first detector or mixer tube, in which the radio signal frequency and the local frequency, generated in an oscillator circuit by a separate tube or by the mixer tube, are both applied to the same 15 grid of the mixer tube. These methods generally depend on coupling the oscillator and mixer circuits by either capacitive or inductive coupling which requires rather critical adjustment, and due to this coupling changes in the signal input circuit 20 affect the operation of the oscillator and hence the local frequency.

One object of the present invention is to provide an electron discharge tube with high gain and in which heterodyne action may be obtained 25 without undesired intercoupling between the input and oscillator circuits.

Another object is to provide an electron discharge tube of the multi-electrode type having two electrodes which may be connected an an 30 external circuit to constitute, in conjunction with the cathode, an oscillator which operates under substantially constant conditions and uninfluenced by reactions from the signal input circuit connected to other electrodes in the tube.

35 A further object is to provide a thermionic electron discharge tube of the multi-electrode type in which in effect the emission from the thermionic cathode can be varied at a predetermined and usually high and constant frequency, thereby in 40 effect modulating the space current by variation of cathode emission, and the cathode stream thus modulated is further modulated and controlled by a control grid and utilized by a plate electrode.

45 A still further object is to provide a tube of this type in which the effects of coupling between the signal input grid and the oscillator electrodes are reduced to such an extent that oscillator frequency radiation is practically eliminated.

50 Further objects and advantages will appear from the more detailed description of the invention.

55 In accordance with my invention the electron discharge tube has a plurality of grid-like auxiliary electrodes interposed between the thermionic cathode and the plate so as to be passed suc-

sively by the electron stream from the cathode to the plate. An oscillator circuit may be connected to the cathode and two adjacent auxiliary electrodes to constitute an oscillator for producing in the tube an electron stream pulsating at the desired local frequency and modified or modulated on its way to the plate by an alternating voltage input or radio signal applied to one of the other auxiliary electrodes which acts as a signal input grid. The electron stream from the cathode is 10 first affected by the oscillator input grid and then by the signal input grid, so that the frequency of the current to the plate and output circuit is the resultant obtained by thus mixing in the tube the local frequency and the input or radio signal frequency to obtain the desired beat or intermediate frequency in the output circuit.

In a commercial tube of this type a capacitive or similar coupling might exist between the oscillator circuit and signal input circuit because the signal 20 input grid is necessarily close to the oscillator electrodes. In order to avoid such coupling and thereby eliminate reaction of the signal input circuit upon the oscillator circuit the signal input grid which is connected with the signal circuit is, 25 in accordance with my invention, free from appreciable capacitive coupling to the oscillator electrodes. In one embodiment of my invention this result is attained by electrostatically screening the signal input grid in the signal input circuit from the electrodes in the oscillator circuit, 30 preferably by interposing between the signal input grid and the adjacent oscillator input electrode a grid-like shield or screen maintained at a constant direct potential, which may be substantially 35 zero with reference to the cathode of the oscillator, to prevent alternating electromotive forces on the signal input grid and adjacent oscillator electrodes causing reactions between the oscillator circuit and the signal input circuit. In 40 another embodiment, means are provided for establishing in the space between the input grid and the oscillator electrodes a space charge which pulsates at the frequency of the oscillator and is in effect a virtual cathode which varies in emission. The preferred construction in this embodiment of my invention is an ancillary grid-like electrode interposed between the oscillator input electrode and the signal input grid and maintained at a positive potential sufficiently to attract 45 the electrons emitted by the thermionic cathode, and of sufficient open mesh to permit a large part of the electron stream to pass through it. Where the electrodes are coaxially mounted in the usual way this ancillary grid-like electrode surrounds 50

the oscillator electrodes and in effect encloses them in a kind of open mesh cage.

The signal input grid surrounding the ancillary electrode modulates the discharge substantially as through a pulsating space charge or virtual cathode between the ancillary grid and the signal input grid were the only cathode in the tube. A grid interposed between the plate and the input grid may be maintained at a positive potential somewhat below that of the plate in order to screen the signal input grid from the plate and may, if desired, be connected, preferably within the tube, to the ancillary grid between the oscillator input electrodes and the signal input grid.

In the preferred construction only sufficient energy for suitable operation of the oscillator circuit is abstracted from the electron stream by the electrode which acts as an oscillator anode and which is connected in the oscillator circuit through a tickler or feed-back coil in the usual way, the remainder of the electron stream passing through the tube to the plate and to the output circuit. The oscillator anode electrode may be either a grid of very open construction, or consist of one or more rods so positioned with reference to the other electrodes that only a portion of the electron stream from the cathode is intercepted by it. Modulation of the electron stream received at the plate is effected by both the oscillating voltage on the oscillator input grid, and by the signal voltage applied to the signal input grid.

The signal input grid may to advantage be of the multi-mu type, particularly where automatic volume control is desired. It has been found that where a signal input grid of this type is used the distance of the signal input grid from the ancillary electrode enclosing the oscillator electrodes must be greater than the distance at which an input grid should be placed from an equi-potential cathode in the position of the ancillary electrode.

The novel features which I believe to be characteristic of my invention are pointed out with particularity in the appended claims. The invention itself, however, both as to its organization and method of operation, together with further objects and advantages thereof will best be understood by reference to the following description taken in connection with the accompanying drawings in which:

Fig. 1 shows, partly in longitudinal section, one embodiment of my invention in an electron discharge tube; Fig. 2 is a cross-section of the tube along the line 2—2 of Fig. 1; Figs. 3 and 4 show, in longitudinal section, modifications of parts of the tube shown in Fig. 1; Fig. 5 is a circuit diagram for the tube shown in Fig. 1; Fig. 6 is a circuit diagram for the modification shown in Fig. 3; and Fig. 7 is a circuit diagram for the tube shown in Fig. 1 when made with a filamentary cathode.

The electron discharge tube shown in Fig. 1 comprises a highly evacuated bulb 10 with the usual re-entrant stem 11 on which the electrode assembly is carried. Two parallel support rods 12 project from the stem and carry two parallel insulating bars or spacers 13, preferably of mica, which extend transversely of the support rods and are secured to them by metal fasteners 14. A cylindrical plate 15, preferably of blackened or carbonized nickel, is fastened to the support rods. The grids and the cathode, all carried on and supported by the transverse bars 13, are mounted between the bars and coaxially of the plate 15. The equi-potential cathode is of the usual type,

comprising a reverse coiled tungsten filament heater surrounded by a straight nickel sleeve 16 coated with oxides of barium and strontium, and having a cathode connector 17 joined to a bent cathode lead 18 which also carries the getter tab 19.

The auxiliary electrodes or elements interposed between the cathode and plate so as to be passed in succession by the electron stream from the cathode to the plate are in the form of grids, preferably arranged coaxially with the cathode. Unless otherwise specified, they are the usual wound grids, each consisting of two parallel grid rods and a helix of fine cylindrical grid wire with its turns fastened to the grid rods, the ends of which fit snugly into holes in the transverse spacers or bars 13. Adjacent and surrounding the cathode is the No. 1 auxiliary electrode or oscillator input grid 20, preferably elliptical in cross-section. The next, or No. 2 auxiliary electrode 20 acts as the oscillator output electrode or anode, and is a grid-like anode electrode 21 constructed to draw only a fraction of the cathode current, and which preferably has no grid wire, but is merely two grid rods mounted on the stem in alignment with the grid rods of the oscillator or No. 1 grid 20, and electrically connected to each other, preferably at the top, as shown in Fig. 1. This grid-like anode electrode may be made in many different ways to draw only a portion of the cathode current. The next, or No. 3 auxiliary electrode, is the ancillary grid 22, which, as shown in Fig. 2, is also elliptical in cross-section, with its long axis in alignment with the grid rods of the other grids. The next, or No. 4 auxiliary electrode, is a cylindrical signal input grid 23, preferably of the multi-mu type, and shown in Fig. 1 as a helical grid of progressively varying pitch, although other well known forms of multi-mu grids may be used. The signal input grid is connected to a contact cap on the tip of the bulb. The next, or No. 5 auxiliary electrode, is a cylindrical screen grid 24 mounted coaxially with and between the signal input grid 23 and the plate 15, and electrically connected to the ancillary grid 22 through a bent lead 25 to which both grids are connected.

In a tube constructed as shown in Fig. 1 and design in accordance with the usual practice for a cathode current of about 11 milliamperes and a plate voltage of about 250 or 100 volts, the grid-like anode electrode may be operated at about 250 or 100 volts, and the ancillary grid and screen grid at about 100 or 50 volts. In such a tube it has been found that the distance between the flattened sides of the elliptical ancillary grid 22 at the ends of the short axis of the grid and the cylindrical signal input grid 23 should be about one-eighth of an inch, a distance much greater than that at which the input grid would be placed were the ancillary grid 22 a uni-potential cathode. The exact distance depends on the cathode emission, the construction of the signal input grid, and the operating voltage of the tube. If the signal input grid is too close to the ancillary grid, the multi-mu effect is not obtained.

Fig. 3 shows a modification in which the No. 3, or ancillary grid is in effect a shielding grid 26, proportioned to act as an electrostatic screen. It is rather close meshed, but the electrons can pass through it, and it is connected inside the tube directly to the cathode through the cathode lead 18 thereby making the grid 26 a grounded shield between the signal input grid and the two oscillator electrodes 20 and 21 adjacent the

cathode. This modification shows the No. 2, or oscillator anode grid 21, made as the usual wound grid with a pitch such that it is of very open mesh, so that it accelerates the electrons from the cathode, but intercepts only a comparatively small part of the electron stream, permitting the remainder to pass on to and through the shielding grid 26.

Fig. 4 shows a modification in which the tube 10 is practically a triode and a hexode side by side in the same bulb with a common cathode, as the No. 2, or grid-like anode electrode, has on the two grid rods near one end a sheet metal grid cylinder 27 much shorter than the other electrodes. The 15 tube is practically a triode at the end of the cathode covered by the grid cylinder 27, and a hexode at the uncovered and major portion of the cathode.

Fig. 5 shows the tube illustrated in Fig. 1 connected in circuit for use in superheterodyne reception. A conventional input circuit 28 is connected to the signal input grid, and a conventional tuned load or output circuit 29 is connected to the plate 15. The cathode, grid 20, and anode 25 grid 21 are connected to an oscillator circuit 30 of conventional design and comprising a feedback coil 31 connected to the oscillator output electrode or anode grid 21. The voltages for operating the tube may be obtained from taps on a resistor 32.

In the operation of the tube connected as shown in Fig. 5 the cathode, oscillator grid 20, and grid-like anode electrode 21 constitute the three electrodes of an oscillator. All of the electron stream from the cathode is modulated by the oscillator grid 20, but only enough of the stream is intercepted by the output electrode or anode grid 21 to supply sufficient current through the coil 31 to keep the oscillator in operation. 40 The two parallel rods projecting from the stem and constituting the anode electrode 21 are in alignment with and shielded from the cathode by the side rods of the oscillator grid 20 to such an extent that only a fraction of the electron current 45 emitted by the cathode reaches the anode electrode 21. The remainder of the electron stream or current from the cathode, modulated by the oscillator grid 21, passes directly to the ancillary grid 22, which is sufficiently positive, usually 50 about 100 volts, to draw the electrons to and through it, and to form between the ancillary grid 22 and the control grid 23 a space charge which responds to the signal input grid like a virtual cathode with an emission pulsating at the frequency 55 of the oscillator.

The ancillary grid 22 is connected to the positive voltage source through a low impedance connection, so that it is held at constant direct current potential which does not change with the 60 modulation. It is not an anode in the usual sense, as it draws only grid current, which is a very small portion of the cathode current, but it is essentially an accelerating electrode for the modulated electron stream from the cathode. It is 65 not an element of the oscillator and takes no part in its operation. So far as capacity coupling of the oscillator current to the signal input grid is concerned, the oscillator electrodes inside the ancillary grid are practically non-existent, and in 70 effect the cathode for the signal input grid and the plate is the virtual cathode around the ancillary grid. It has been found that the use of the positive ancillary grid also reduces to a marked extent the local frequency radiation.

75 It has been found advantageous by adjustment

of the circuit to operate the oscillator grid at a bias of about 60 volts negative, and when so operated the cathode current flows only while the oscillator grid is swinging between 20 volts negative and enough volts positive to utilize the cathode current to the best advantage. The result is a pulse of cathode current through the tube during the middle portion of that half cycle of the oscillator when the anode grid 22 is positive, and no cathode current through the tube during the remainder of the cycle, as no current flows during the other half cycle of the oscillator when the anode grid is negative. These pulses of cathode current flowing practically unimpeded to and through the ancillary grid 22, produce near 15 the outside of the ancillary grid a space charge which pulsates at oscillator frequency and acts as a virtual cathode.

The load condenser in the plate circuit should be of sufficient size to limit the magnitude of 20 the radio frequency voltage built up across the load and thus prevent radio frequency voltage feed-back between the plate and the signal input grid and consequent degenerative effects.

Converter circuits such as shown in Fig. 5 and 25 employing a tube constructed in accordance with my invention may easily be designed to have a translation gain as high as approximately 60.

The circuit in Fig. 6 is substantially the same as in Fig. 5, except that the shielding grid 26 is 30 connected, preferably inside the tube, directly to the cathode and hence is at zero potential with reference to it.

Fig. 7 shows the same circuit as Fig. 5 connected to a tube construction as in Fig. 1 but with a 35 filamentary thermionic cathode 33. This circuit illustrates the simplicity of the circuit connections adequate for an oscillator detector tube constructed in accordance with my invention, as contrasted with the complex and expensive circuit connections required and commonly used with a filamentary cathode tube used as an oscillator.

A tube constructed in accordance with my invention has the advantages of requiring less 45 space, as one tube takes the place of the two tubes heretofore required; high conversion conductance; no radiation of the oscillator frequency with the signal system; simplified associated 50 circuits without any coupling; and a constancy of oscillator frequency unaffected by wide variation in the voltage on the signal input grid.

While I have illustrated and described the preferred embodiments of my invention it is by no means limited to the precise construction or 55 circuit arrangement shown, as many variations in the structural details as well as the manner in which it is used may be made without departing from the scope thereof as set forth in the appended claims.

Having thus described my invention, what I claim is:

1. In an electron discharge device, the combination with a thermionic cathode, a plate, and two input electrodes located between said cathode and said plate at different distances from said cathode, of a grid-like anode electrode of coarser mesh and a grid-like screen electrode of finer mesh than said input electrodes and interposed between said input electrodes with said 70 anode electrode interposed between said screen electrode and the input electrode which is nearer said cathode.

2. In an electron discharge device, a thermionic cathode, a plate, and a plurality of auxil-

5 iary electrodes interposed between said cathode and said plate to be passed successively by the electron stream from said cathode to said plate and comprising an input grid adjacent said cathode, a grid-like anode electrode adjacent and of more open mesh than said input grid, an ancillary gridlike electrode adjacent and of closer mesh throughout its length than said anode electrode, and a second input grid between said ancillary grid electrode and said plate.

10 3. An electron discharge device comprising an evacuated envelope enclosing a thermionic cathode, a plate, an output electrode adjacent said cathode, an input grid electrode of finer mesh than said output electrode interposed between said cathode and said output electrode, a signal input grid between said output electrode and said plate, and a shield grid electrode of finer mesh than said output electrode interposed between said output electrode and said signal grid and connected inside said envelope to said cathode.

15 4. An electron discharge device comprising an evacuated envelope enclosing a thermionic cathode, a plate, an output electrode adjacent said cathode, an input electrode between said cathode and said output electrode, an elliptical ancillary grid surrounding said output electrode and said cathode, and a circular input grid of non-uniform pitch surrounding said ancillary grid and spaced from said ancillary grid a distance sufficient to cause said device to operate as a multi-mu device.

20 5. An electron discharge device comprising an evacuated envelope enclosing a thermionic cathode, a plate, an output electrode adjacent said cathode, an input electrode between said cathode and said output electrode, an elliptical ancillary grid surrounding said output electrode and said cathode, and a circular input grid of non-uniform pitch surrounding said ancillary grid and spaced from said ancillary grid a distance considerably greater than the distance necessary to space said input grid from an equipotential cathode in the position of said ancillary grid to obtain the same multi-mu effect.

25 6. An electron discharge device comprising a thermionic cathode, a plate, a plurality of cylindrical grids of different diameters coaxial with said cathode and each comprising a pair of parallel grid rods and a helix of grid wire mounted on said grid rods, the grid rods of said grids being in alignment, and an anode electrode consisting of a pair of electrically connected rods mounted between two of said grids in alignment with the grid rods thereof.

30 7. An electron discharge device comprising an envelope enclosing a thermionic cathode, a cylindrical plate, four cylindrical grids of different diameters coaxial with said cathode and each comprising a pair of parallel grid rods and spaced grid wires transverse to said grid rods, the two grids nearest said cathode being elliptical in cross-section, and the other two grids circular in cross-section, a pair of electrically connected parallel rods between and in alignment with the grid rods of said elliptical grids, and a direct connection inside said envelope between the said elliptical grid furthest from said cathode and the cylindrical grid nearest said plate.

35 8. An electron discharge device comprising a thermionic cathode, a helical input grid surrounding said cathode, an ancillary helical grid surrounding said cathode and said helical input grid, a second helical input grid surrounding said ancillary grid, a grid anode interposed between

4 said first input grid and said ancillary grid and of more open mesh than any of said grids, and a plate surrounding said second helical input grid.

5 9. An electron discharge device comprising a thermionic cathode, a plate, a plurality of cylindrical grids of different diameters coaxial with said cathode and each comprising a pair of parallel grid rods and spaced grid wires extending between said grid rods, said grids being mounted 10 with their grid rods in alignment, and an anode electrode comprising a pair of parallel rods mounted outside of and in alignment with the grid rods of said grid adjacent said cathode and inside and in alignment with the grid rods of the 15 next grid, and a metal strip mounted on and extending transversely of said pair of parallel rods and located in registry with only a minor portion of the active surface of said cathode.

20 10. In an electron discharge device the combination with a thermionic cathode, of two elliptical grids of different diameters coaxial with said cathode and each comprising a pair of parallel grid rods and a flattened helix of fine wire secured to said grid rods, said pairs of grid rods 25 being mounted in alignment, and an anode electrode outside the main electron stream from said cathode to said outer grid and comprising a rod mounted between and parallel to the adjacent grid rods of said elliptical grids.

25 11. In an electron discharge device the combination with a thermionic cathode, of an input grid surrounding said cathode, an open anode adjacent said input grid and consisting of conductors spaced to provide a more open mesh than said input grid and to intercept only a portion of the electron stream flowing from said cathode past said anode, and a grid electrode of finer mesh throughout its length than said anode coaxial with said cathode and surrounding said input grid and said anode.

30 12. In an electron discharge device the combination with a stem and an elongated thermionic cathode mounted in alignment with the axis of said stem, of an inner grid surrounding 45 said cathode, an anode electrode outside of said inner grid and consisting of a pair of electrically connected rods extending from said stem parallel to and on opposite sides of said cathode, and an outer grid exposed throughout its length 50 to said anode electrode and coaxial with and surrounding said cathode, said inner grid, and said pair of rods.

35 13. An electron discharge device comprising a thermionic cathode, a plate, and a plurality of 55 auxiliary electrodes interposed between said cathode and said plate to be passed successively by the electron stream from said cathode to said plate and comprising a multi-mu input grid of non-uniform mesh, another input grid electrode 60 juxtaposed to said cathode, and an anode grid electrode of coarser mesh than said other input electrode interposed between said input grids.

40 14. An electron discharge device comprising a thermionic cathode, a plate, and a plurality of 65 auxiliary electrodes interposed between said cathode and said plate to be passed successively by the electron stream from said cathode to said plate and comprising a helical input grid juxtaposed to and surrounding said cathode, an anode grid surrounding and of more open mesh than said input grid, a second helical input grid surrounding said anode grid and of non-uniform pitch, and a screen grid of finer mesh than said 75

- anode grid and surrounding said second input grid.
15. An electron discharge device comprising a thermionic cathode, two tubular grid electrodes surrounding and coaxial with said cathode, an output electrode consisting of a pair of rods parallel to and on opposite sides of said cathode and positioned between said two grid electrodes, another tubular grid electrode of non-uniform pitch surrounding and coaxial with said two grid electrodes, and a tubular plate surrounding and coaxial with all said grid electrodes.
16. An electron discharge device comprising a thermionic cathode, two cylindrical grids of successively increasing diameters coaxial with said cathode and elliptical in cross-section, a grid-like anode electrode interposed between and of more open mesh throughout its length than said two elliptical grids, a third cylindrical grid circular in cross-section and surrounding said elliptical grids and having non-uniform grid spacings, and a cylindrical plate surrounding said circular grid.
17. An electron discharge device comprising an envelope enclosing a thermionic cathode, a cylindrical plate, four cylindrical grids of successively increasing diameters coaxial with and surrounding said cathode, a grid-like anode electrode interposed between the first and second grids from the cathode and of more open mesh throughout its length than said second grid, and a direct connection inside said envelope between said second grid and the fourth grid from the cathode.
18. An electron discharge device comprising a thermionic cathode, a plurality of tubular grid electrodes coaxial with and surrounding said cathode and of successively increasing diameters, a grid-like anode electrode between the first and second grid electrodes from the cathode and of more open mesh throughout its length than either of said grid electrodes, a third grid electrode having non-uniform grid spacings and surrounding said second grid electrode, and a tubular plate surrounding said third grid electrode.
19. An electron discharge device comprising a thermionic cathode, a cylindrical plate, a plurality of grid-like electrodes interposed between said cathode and said plate to be passed in succession by the electron stream from said cathode to said plate and including three tubular grids of successively increasing diameters, the smallest diameter grid being close to the cathode, the intermediate diameter grid elliptical in cross-section, and the largest diameter grid circular in cross-section and surrounding said intermediate elliptical grid.
20. An electron discharge device comprising a thermionic cathode, a cylindrical plate, five grid-like electrodes interposed between said cathode and said plate to be passed in succession by the electron stream from said cathode to said plate, the first grid-like electrode being nearest said cathode, the second grid-like electrode from said cathode constituting a grid-like anode of more open mesh throughout its length than the first grid-like electrode, the third grid-like electrode from said cathode being curved to the surface of an ellipse and of finer mesh than said first grid-like electrode, the fourth grid-like electrode from said cathode being curved to the surface of a circular cylinder and having non-uniform grid spacings, and the fifth grid electrode from said cathode being nearest said plate.
21. An electron discharge device comprising a thermionic cathode, a plate, a pair of input grids in series relation in the path of the discharge from said cathode to said plate, a grid-like anode of more open mesh than said input grids mounted between said grids in the path of said discharge, and a screen grid of finer mesh than said anode mounted between said anode and the second input grid to electrostatically isolate said anode from said second input grid and said plate.
22. An electron discharge device comprising a thermionic cathode, an input grid surrounding said cathode, two other tubular grids of different diameters coaxial with and surrounding said input grid, the inner one of said two tubular grids being elliptical and the other circular in cross-section, and a tubular plate surrounding said grids.
23. An electron discharge device comprising a thermionic cathode, an input grid surrounding said cathode, two other tubular grids mounted coaxial with and surrounding said input grid, the inner grid being elliptical and the other circular in cross-section, one of said tubular grids being of non-uniform mesh, and a tubular plate surrounding said grids.
24. An electron discharge device comprising a thermionic cathode, an input grid surrounding said cathode, a grid electrode surrounding said grid and imperforate over part of its length and comprising over another part of its length a pair of spaced conductors, and an electrode surrounding said grid electrode.
25. An electron discharge device comprising a thermionic cathode, two tubular grids of different diameters coaxial with and surrounding said cathode, an imperforate anode shorter than and interposed between said grids to extend transversely of the longitudinal axes of said grids, and a tubular anode coaxial with and surrounding said grids and longer than said imperforate anode.

DONALD G. HAINES.
